(57) **CLAIM**

An ornamental design for a razor device, as shown and
described.

DESCRIPTION

FIG. 1 is a first perspective view of an embodiment of a
razor device, showing the razor device in a closed position.

FIG. 2 is a second perspective view of the embodiment of
the razor device in the closed position shown in FIG. 1.

FIG. 3 is a first side view of the embodiment of the razor
device in the closed position shown in FIG. 1.

FIG. 4 is a second side view of the embodiment of the razor
device in the closed position shown in FIG. 1, the second
side being generally opposite to the first side shown in FIG.
3.

FIG. 5 is a top view of the embodiment of the razor device
in the closed position shown in FIG. 1.

FIG. 6 is a bottom view of the embodiment of the razor
device in the closed position shown in FIG. 1.

FIG. 7 is a front view of the embodiment of the razor device
in the closed position shown in FIG. 1.

FIG. 8 is a back view of the embodiment of the razor device
in the closed position shown in FIG. 1.

FIG. 9 is a first perspective view of the embodiment of a
razor device shown in FIG. 1, showing the razor device in
an open position.

FIG. 10 is a second perspective view of the embodiment of
the razor device shown in FIG. 1, showing the razor device in
an open position.

FIG. 11 is a first side view of the embodiment of the razor
device shown in FIG. 1, showing the razor device in an open
position.

FIG. 12 is a second side view of the embodiment of the razor
device shown in FIG. 1, showing the razor device in an open
position, the second side being generally opposite to the first
side shown in FIG. 11.

FIG. 13 is a top view of the embodiment of the razor device
shown in FIG. 1, showing the razor device in an open
position.

FIG. 14 is a bottom view of the embodiment of the razor
device shown in FIG. 1, showing the razor device in an open
position.

FIG. 15 is a front view of the embodiment of the razor
device shown in FIG. 1, showing the razor device in an open
position; and,

FIG. 16 is a back view of the embodiment of the razor device
shown in FIG. 1, showing the razor device in an open
position.

(Continued)

The broken lines in FIGS. 9-11 depict environmental structure and form no part of the claimed design.
